WREATH FORMING MACHINE

Henry O. Englert, Auburn, Wash.

Application November 7, 1950, Serial No. 194,551

5 Claims. (Cl. 41—3)

1

This invention relates to devices or machines for use in the making of decorative wreaths. More particularly, it has reference to a machine for use in the making of circular wreaths from small branches, twigs, stems or limbs of cedar, holly, fir, pine and the like, as well as from ferns, vines, flowering shrubs and climbing plants that lend themselves to circular formation.

It is the principal object of this invention to provide a machine whereby wreaths may be easily, quickly and economically made, from materials of the kinds above listed, in uniform size and adequately tied to insure the maintenance of their form while in use.

It is a further object of the invention to provide a machine of the above stated character, comprising a platen on which the wreath forming material can be quickly arranged and held in the desired, circular form, a plate for compressing the material for tying, and a manually operable wire feeding device whereby the end of a wire as extended from a spool or source of supply may be placed in position for being tied about the wreath forming material as held in the platen.

Another object of the invention is to provide a machine of the above character wherein the wire feeding device is located at one side of the machine, and the platen is adapted to be rotatably indexed and is provided at its periphery with equally spaced and radially directed slots for the passing of the wire feeding device therethrough with the successive indexing movements of the platen.

Yet another object of the invention is to provide a machine for the making of wreaths that, by reason of its simplicity and easy mode of operation, lends itself to use by blind persons.

Still further objects of the invention reside in the details of construction of the various parts, and in their combination and mode of operation, as will hereinafter be fully described.

In accomplishing the above mentioned and other objects of the invention, I have provided the improved details of construction, the preferred forms of which are illustrated in the accompanying drawings, wherein—

Fig. 1 is a side elevation of the present machine.

Fig. 2 is a top view of the machine, a part of 50 the press plate being broken away for the showing of underlying parts.

Fig. 3 is a cross-section of the wreath forming platen, the press plate and shuttle, as seen in line 3—3 in Fig. 2.

2

Fig. 4 is a sectional detail of one of the press plate holding dogs.

Fig. 5 is an enlarged, longitudinal section of the wire feeding device and a part of its supporting and operating lever.

Fig. 6 is a sectional detail of the turret indexing stop.

The device of the present invention, is designed for the holding of wreath forming materials, of the kinds previously named, in circular form, and the application of tie wires about the secured material to maintain the material in wreath form when removed from the machine; the device being so constructed that the accurate, 15 satisfactory and economical making of wreaths of uniform size can be accomplished, even by persons who are blind. In brief, the device comprises a rotatably mounted platen on which pieces of material used can be easily and readily 20 assembled and held in circular wreath form; a press plate for compressing and holding the material for tying and a wire feeding device that is manually operable for passing of wire ties about the formed material for its secure- 25 ment in wreath form when removed from the platen.

Referring more in detail to the drawings—

The machine comprises a flat horizontally disposed base 10 upon which, at its center, a standard 11 is rigidly mounted. The base and standard may be of wood, metal or other suitable materials, and their size, shape and height may be varied to meet requirements, without departing from the spirit of the invention.

Rigidly fixed upon the upper end of the standard is a horizontally disposed plate 12, and rotatably secured thereon is the platen by means of which the wreath forming materials are assembled and held in wreath form for tying. This platen comprises a flat, circular, base plate 13 of a diameter somewhat greater than that of the wreaths to be formed, and secured concentrically upon a plate 14 of substantially lesser diameter by means of a plurality of bolts 15; these bolts being projected upwardly through the plates, with their heads seated in sockets 16 in the under side of plate 14, and with wing nuts 15x threaded onto their upper ends and tightened against the plate 13.

The platen as embodied by plates 13 and 14 is rotatably secured upon the standard by a central pivot bolt 17. This bolt extends upwardly through the plate 12, in the axial line of the standard, and through a central hole 18 in the plate 14, and is there secured by nuts 19 applied

to its upper end. It is well shown in Fig. 3 that the plate 13 has a large hole 20 coaxially therethrough and a metal washer 21 is fitted in the bottom of this hole against the top side of the plate 14. The washer 21 serves as a wear plate and it is through this plate that the bolt 17 extends.

It is also shown in Fig. 3 that a metal wear plate or disk 22 is disposed between the plates 12 and 14 and is secured to the under side of plate 14 by screws 23 passed upwardly therethrough into plate 14.

Mounted in the plate 13 and extended upwardly from its top side are two concentric rows of pins or pegs 24. The pins of the two rows are equally angularly spaced and each row, in the present instance, is shown to comprise twelve pins. Also, the pins as applied to the inner and outer rows are radially aligned on the plate. In the formation of a wreath, the selected material is placed between these two circular rows of pins and is thereby held in circular form for compression and tying together.

It is also to be observed by reference to Figs. 2 and 3, that the plate 13 is formed with radial slots 25 that lead thereinto from the outer periphery to a distance beyond the inner circle of pins 24; these slots being located between the radially aligned pins in the two circular rows as well shown in Fig. 2.

Associated with the plate 13 is a circular disk or plate 30 referred to as the "press plate." This is adapted to be horizontally disposed upon the platen as shown in Fig. 3, and preferably is of the same diameter as plate 13, and formed with radial slots 31 that are located directly above those in plate 13, when the plate 30 is in use. The plate 30 also is formed with holes 32 for the easy passage therethrough of the pins of the two circular rows when the press plate is assembled with the platen, and is formed with holes 33 in alignment with the wing nuts 15 as applied to bolts 15 in order that these nuts will not interfere with the press plate being brought down close to plate 13.

In the use of the machine, the press plate is applied to the platen after material to form a wreath has been properly placed between the concentric rows of pins 24. It is used to compress and hold the wreath forming material to the extent desired while the tie wires are applied thereto.

To hold the press plate securely in a clamping position, it is equipped at diametrically opposite sides with grippers 35-35, each of which comprises a short strip of spring steel secured at its inner end, which is within the inner circle of pins 24, to the press plate by screws 36. The spring strips are in radial alignment with aligned pins of the two circular rows of pins. Adjacent its point of securement each strip is bent upwardly as at 36x and then downwardly and outwardly as at 36y to extend beyond the inner row of pins and then is bent to extend horizontally beyond the periphery of the disk. The strips 35 are formed with holes 37-37 for the passage of the aligned pins therethrough. The size of the holes that receive the pins of the inner row and the slope of the spring strip is such that a firm holding of the grip strip with the pin is automatically effected to hold the press plate against lifting after being pressed down against the wreath material. However, the grip strip can be easily and readily released by pulling their free outer ends upwardly relative to the press plate.

After wreath forming material has been properly laid on the platen between the rows of pins 24, and has been compressed and secured by the press plate, it is tied by the application of wire ties thereabout. This is accomplished in part by use of the wire feeding device best shown in Figs. 1 and 5.

The wire feeding device comprises a tubular barrel 40 onto the upper end of which a conical tip 41 is removably threaded. The tip is formed with a coaxial passage 41' for the passage of the tie wire, such as that designated by reference character *w*. As a means of applying tension to the wire, to prevent its free running in the wire feeding device, a short rubber plug or core 42 is fitted in the barrel 40 adjacent the tip. This core has a small central hole 43 through which the wire can be pulled. However, the plug, applies a desired holding friction on the wire that prevents its unthreading after being cut for the tieing operation.

The wire feeding device is rigidly mounted to extend upwardly and inwardly from the outer end of an operating arm 50. The arm extends radially outward from the upper end portion of the standard 11, to which it is pivotally fixed by a pivot pin 51. The arm is adapted to be oscillated in a vertical plane and by this action to cause the wire feeding device to be swung upwardly and projected through aligned slots of the platen and press plate as shown in full lines in Fig. 1, and to be retracted to a position below the platen, as shown in dotted lines.

It is shown in Figs. 1 and 3 that a spool 55 carrying a supply of suitable wire is rotatably supported from the outer end of the arm 50 by a supporting rod 56. The wire *w* can be easily drawn from the spool and passed through the wire feeding device 40 and from the conical tip. When the wire feeding device is in its upper position, it will project through aligned slots of the platen and press plate upward beyond the top of the press plate at the inside of the formed material, as in Fig. 3.

The means for manual operation of the wire feeding device comprises a foot treadle or lever 60 pivoted to the standard 11, near its lower end, by pivot bolt 61 and extended outwardly therefrom. A link 62 is pivotally connected to the treadle as at 63, and to the shuttle mounting lever arm as at 64. A stop 65 on the arm 50 engages the standard to limit the upward swing of the wire feeding device and a coiled spring 66 is attached under tension to the standard and to the treadle to yieldingly hold the wire feeding device at its upper limit of travel, that being the position in which it is shown in Fig. 3.

The wire feeding device may be retracted by downward pressure against the foot plate 68 on the outer end of the treadle.

The application of wire ties to the wreath at regularly spaced intervals calls for the indexing of the platen for the passing of the wire feeding device upwardly through the various slots of the platen and press plate. To insure easy and accurate indexing, I have provided the plate 22 on its under side with a circular row of equally spaced ball seats 69. These are spaced angularly in accordance with the spacing of slots of the platen. Fixed in the plate is a ball cartridge 70 in which a ball 71 is held and pressed upwardly by a spring 72. The ball is arranged to engage in the ball seats as the platen is rotatably advanced, thus to insure the proper locating of the plate slots relative to the position off the wire

feeding device. However, slight rotative force applied to the platen will unset the ball and permit an indexing operation.

Assuming the parts to be so constructed and assembled the use of the device for making a wreath is as follows:

First the wire, which is preferably a fine, soft aluminum wire, is threaded from the spool through the wire feeding device. To permit easy threading, the tip 41 is first removed from the barrel 40 and the rubber core lifted out. Then the wire is projected upwardly through the barrel 40 and through the hole in the rubber core, and through the tip. The core is then reseated in the barrel and the tip applied.

The press plate is removed from the platen and the wreath material placed by hand in the form that is defined between the two rows of pins projecting upwardly from the plate. If desired one or more wire loops may be laid in the form before the wreath is formed. Then the press plate is applied and pushed down to compress and hold the material in place for tieing. This is accomplished by grasping the end of the wire as extended beyond the shuttle tip as shown in Fig. 3, and pulling it out to a required length, then depressing the pedal and grasping the wire just below the platen and cutting it at the point, then pulling the lower end of the cut wire tie about the wreath and securing the ends of the tie. The tie is thus located about the wreath material as exposed in the slots of the platen and press plate. The platen is then indexed one interval, and the wire feeding device returned to normal position by the spring 66 upon release of pressure on the foot treadle.

This tieing operation is repeated until the wreath has been properly secured, whereupon the press plate is lifted off and the finished wreath removed.

Having thus described my invention, what I claim as new therein and desire to secure by Letters Patent, is:

1. A machine for the making of wreaths comprising a support, a circular platen mounted on said support, two spaced, circular rows of pins fixed in the platen, perpendicular thereto and coaxially thereof to receive wreath forming material between them, a press plate disposed above the platen to coact therewith for the compacting of the wreath forming material as held between the rows of pins; said press plate having holes therethrough for the free passage of the said pins upwardly therethrough, and said platen and press plate having radially directed slots formed therethrough, in vertical alignment and extending across the space between the two rows of pins to the inside and outside thereof, and a manually operable wire feeding device mounted by said support for passing of wire ties through aligned slots for securement about the wreath forming material while held under compacting pressure by the press plate.

2. A machine as recited in claim 1 wherein said radial slots open to the peripheries of the platen and press plate and wherein the said wire feeding device is mounted below the platen for

passing the end portion of a tie wire upwardly through vertically aligned slots of platen and press plate at the inside of the wreath forming material as held between the rows of pins; said wire feeding device comprising a tubular barrel through which the end of the wire is threaded and a vertically movable mounting means for the barrel operable upwardly to move the tubular barrel upwardly and endwise through the slots and operable downwardly to withdraw it to a position below the platen.

3. A machine for the making of wreaths comprising a standard, a base plate fixed horizontally thereon, a circular platen mounted for axial rotation on the base plate, two spaced circular rows of pins fixed in the platen perpendicular thereto and coaxially thereof to receive wreath forming material between them, a press plate disposed above the platen to coact therewith for the compacting of wreath forming material as held between the two rows of pins; said press plate having holes therethrough for the free passage of the pins in the functional application of the press plate, means on the press plate arranged to grip certain pins to hold the plate in a compacting position; said platen and said press plate having radially directed slots formed therein in vertical alignment and extending across the space between the rows of pins to the inside thereof and having ends open to the peripheries of the platen and press plate, and a wire feeding device mounted on the standard below the platen, with which the slots of the latter may be registered by rotative adjustment of the platen; said wire feeding means comprising an arm mounted on the standard for oscillation in a vertical plane, a tubular barrel fixed to the outer end of the arm and through which barrel a tie wire is threaded, and a manually controlled means on the standard for actuating the arm to a lowered position at which the barrel is disposed below the platen, and to a raised position whereby the barrel is caused to be projected endwise and upwardly through aligned slots of the platen and press plate, at the inside of the rows of pins.

4. A machine as recited in claim 3 wherein the said manually controlled means comprises a foot pedal pivoted on the standard, a link pivotally connecting the lever and arm whereby the barrel is mounted, and a spring attached under tension to the foot pedal and standard to actuate the pedal and arm upwardly when foot pressure is removed from the pedal.

5. A machine as recited in claim 3 wherein a reel is mounted on the arm of the wire feeding means and said tie wire is drawn from a supply wound on said reel and is threaded directly through the barrel.

HENRY O. ENGLERT.
